ELECTRIC DISCHARGE LAMP

Victor James Francis, North Wembley, and John
Walter Ryde, London, England, assignors to
General Electric Company, a corporation of
New York

Application March 2, 1937, Serial No. 128,687
In Great Britain February 20, 1936

4 Claims. (Cl. 176—122)

This invention relates to high-pressure mercury-vapour electric discharge lamps of the type particularly adapted for use as sources in optical projection apparatus. The term "mercury" does not exclude the presence of substances, additional to mercury, whose spectra may contribute substantially to the light from the lamp.

In one well-known kind of high-pressure mercury-vapour lamp, used for street-lighting and similar purposes, the diameter of the envelope enclosing the discharge is some 25 mm., the pressure of the vapour in operation is 1 to 2 atmospheres, and the brightness of the discharge column does not exceed 300 candles per sq. cm.

15 Here and hereinafter brightness means brightness of the brightest part of the discharge column in a plane perpendicular to its length.

It is desirable that sources for optical projection should be of greater brightness. It is known that one way in which greater brightness can be obtained is to increase the vapour pressure of the mercury in operation to 10 atmospheres or more and to decrease the diameter of the envelope. Thus in British patent specification No. 431,923 lamps are described in which the volts per cm. of the discharge path exceed 150 and may attain 400, (which correspond respectively to vapour pressures of about 20 and 100 atm.) and in which the diameter of the envelope does not exceed 3.5 mm.

The primary object of using a narrow envelope is to promote the stability of the column. For when the pressure of the vapour is high, the column is apt to wander irregularly about its mean position under the intense convection currents; such wandering occurs if the lamp is operated with the line between the electrodes vertical, and also if it is operated with that line horizontal, and if, as is then usual, a magnetic field is applied to prevent the column from bowing upwards and approaching the wall; the prevention of such wandering is very important if the lamp is to be used as a source in optical projection. A subsidiary advantage is that it makes the column narrower and therefore brighter than it would be if it carried the same current through vapour at the same pressure in a wider envelope.

When the envelope is so narrow and therefore so near the discharge column, its interior surface is intensely heated. Even if the envelope is of quartz, it would be destroyed if it were cooled externally by natural convection only. Accordingly it is provided in the said specification that the envelope should be artificially cooled, for example by an external water-jacket. A brightness

of 18,000 candles per sq. cm. can thus be obtained; but the useful life of the lamp is apt to be limited by an obscuration of the envelope due to the intense heating of its inner surface. The object of the invention is to produce lamps with a brightness of the order of 10,000 candles per sq. cm. that are much less subject to this obscuration.

It is to be observed that a narrow envelope is not essential to high brightness. In British patent specification No. 434,919 lamps are described in which the diameter of the spherical envelope may be as great as 30 mm., and in which a stable discharge column of high brightness is obtained by making the ratio of the power dissipated in the discharge to the distance between the electrodes greater (preferably much greater) than 100 watt/cm. The said ratio will hereinafter be denoted for brevity by W/l ; if the lamp has running and starting electrodes, "the electrodes" always means the running electrodes. Lamps in which stability is obtained by making W/l very great do not lie within the scope of this invention; in lamps to which the invention relates the pressure of the vapour in operation and the ratio W/l must be such that, if the discharge column were sufficiently far removed from all solid matter (the said pressure and W/l remaining unchanged) it would be unstable. "Unstable" here and hereinafter implies that, during the test for instability, measures are taken to make the mean position of the column coincide, exactly or nearly, with the line joining its ends, either by making that line vertical or by applying a suitable magnetic field.

The invention rests upon two facts, of which the first is obvious when it is pointed out. It is that, since a lamp used for optical projection is required to emit light only within a limited angle, usually less and often much less than 180°, the presence of absorbing matter outside that angle is no serious disadvantage. It may prevent the use of a backing reflector; but if, by rendering the discharge column stable, it enables the watts dissipated per unit volume of the discharge to be increased, the loss of brightness due to the absence of such a reflector is easily offset.

The second fact is a new discovery. It is that, in order to obtain some at least of the advantages, and in particular the stability, resulting from the use of a narrow envelope, it is not necessary to surround the discharge completely by solid matter adjacent to it. If sufficiently powerful forces act on the discharge column perpendicular to its length, driving it towards suitably shaped solid

matter and causing it to lie adjacent to that matter, it is not necessary that there should be solid matter adjacent to the column in directions opposite to that in which it is driven by those forces. Thus, if the straight line joining the electrodes is horizontal so that convection drives the column upwards, stability can be obtained if there is a solid surface concave downwards above the said line, and if the forces of convection driving the column towards that solid surface are sufficiently powerful. When the column is thus forced to lie adjacent to the solid matter above it, its distance from solid matter below it has no effect on its stability. If the solid surface is flat or the forces insufficiently powerful, then, though the solid may limit the bowing upwards of the column, the column will be liable to wander over its surface. Instead of or in addition to convective forces, those arising from a magnetic field may be employed to drive the column towards solid matter on one side of it; again the distance of solid matter in other directions is relatively unimportant.

In virtue of these facts, the solid matter surrounding the line joining the electrodes may be of two different kinds, performing different functions. The function of the matter on the side towards which the column is driven is to be refractory, so as to resist the heat developed in the column adjacent to it; its optical properties are immaterial. The function of the matter on the side away from which the column is driven is to transmit to the exterior the light from the column; transparency is essential, but no more refractoriness is necessarily required than will enable the matter to stand a temperature sufficient to maintain the vapour pressure of the mercury; this temperature must, of course, be attained by all parts of the envelope.

According to the invention in a high-pressure mercury-vapour electric discharge lamp, adapted to be so operated that in full operation the pressure of the vapour is so great and the ratio W/l so small that, if the discharge column were sufficiently distant from solid matter, it would be unstable, the line joining the electrodes has on one side of it refractory solid matter and on another side of it a transparent portion of the envelope, the distance between the said refractory matter and the said transparent portion being so great that when the discharge column is driven towards the refractory matter by forces perpendicular to its length, so as to lie stably adjacent to it, the column is so distant from the transparent portion that this portion undergoes substantially no obscuration during life owing to the heat developed in the discharge column. In operation a lamp according to the invention is to be associated with means (which may be gravity producing convection) producing such forces driving the discharge column towards the refractory matter.

Some explanation of the terms used in the foregoing statement must now be added.

The term "refractory" implies that the matter is not damaged by the heat developed in the column lying adjacent to it. Since the transparency of the refractory matter is unimportant, mere obscuration of an originally transparent substance is not to be regarded as damage. The refractoriness may be inherent in the nature of the matter, so that no cooling of it is necessary to prevent damage; thus it may consist of thoria or even tungsten; but, if it is of metal, the portions adjacent the discharge must be in-

sulated from each other, in order that the discharge shall not be short-circuited. Then the refractory matter need not be, and usually will not be, part of the envelope enclosing the discharge; it may be a partition in or completely across the envelope. But the refractoriness may be acquired from artificial cooling applied to the surface remote from the discharge; then the refractory matter will be usually part of the envelope enclosing the discharge. The refractory matter must be more refractory than the said transparent portion; for otherwise no advantage would be obtained from the distinction between them. But if the refractoriness is acquired solely from cooling, its inherent refractoriness need be no greater. In particular both the refractory matter and the transparent portion may be of quartz, so long as the former is cooled.

The transparent portion will usually be vitreous; but quartz is not essential, since the greatest refractoriness is not required. It must not produce appreciably more unwanted absorption of the light incident on it than the quartz or glass envelope usually enclosing high-pressure mercury vapour lamps. But, of course, if absorption of part of the light emitted from the discharge is wanted (for instance, in order to obtain monochromatic light), the absorbing matter may be on or in the transparent part of the envelope.

The deposition on the transparent portion of matter sputtered or evaporated from the electrodes is not to be regarded as obscuration owing to the heat developed in the discharge column. Some loss of transparency due to this course is likely to occur however great (subject to practical limitations) is the distance of the transparent portion from the discharge. It is almost independent of the obscuration to which the invention is directed, which is due to the high temperature reached by matter near the discharge.

The refractory matter and the transparent portion need not be in opposite sides of the line joining the electrodes; but of course they cannot be on the same side of the line. Thus, if the forces driving the discharge column are convective and the refractory matter has to be above the electrodes, the lamp cannot be adapted to emit light upwards; on the other hand, it can be adapted to emit light horizontally or nearly horizontally as well as downwards.

It is preferable that the surface of the refractory matter towards which the discharge column is driven should be highly curved, so that, when the column is lying adjacent to this surface, it is more closely surrounded by matter than it would be if it lay at the same minimum distance from the transparent portion, which will generally be as nearly flat as is consistent with the general shape of the envelope. The stability of the discharge is in general the greater the more closely it is surrounded by matter. But, if the driving forces are sufficiently strong and sufficiently concentrated in one direction, the discharge may lie stably against a surface whose curvature is no greater, and may possibly be less, than that of the main part of the envelope.

Certain embodiments of the invention will now be described with reference to the accompanying drawing, in which Figures 1, 2, 3 each show a different embodiment. Of these Figure 1 illustrates the use of an inherently refractory partition, Figure 2 the use of a portion of the envelope cooled by forced air circulation as the refractory matter, Figure 3 the use of an applied

water-cooled member to supply the cooling. Each embodiment is to be operated with the top of the figure uppermost; the driving forces may then be purely convective.

- 5 Each figure is a section of the lamp by a plane perpendicular to the line joining the electrodes and midway between them. The point at which this line intersects the plane is indicated by X; but its position may vary somewhat with the 10 length of the said line, which will determine the length of the lamp perpendicular to the plane of the drawing. For the distance between the electrodes will be determined by the voltage of the lamp and the vapour pressure at which it 15 is designed to operate; the distance of X from the solid matter above it must not be so large compared with the distance between the electrodes that the length of the discharge column is increased very greatly when it is driven to lie 20 adjacent to the refractory solid matter. In all cases, if the lamp is designed for 400 watts, the vertical distance between the solid matter above and below X may be about 20 mm.

In Figure 1 the envelope directly enclosing the 25 discharge is a quartz tube 1 of circular section, whose lower part is the said transparent portion. The refractory solid matter is a V-shaped plate 2 of thoria, substantially coextensive in 30 length with the discharge path inserted as a partition in the tube, with its apex upwards. The column is forced to lie near the apex by the convective forces, so that it is closely surrounded by solid matter.

In Figure 2 the envelope directly enclosing the 35 discharge is the lower half 4 of a quartz tube 1 (which half is the transparent portion) and a quartz partition 5 sealed across the tube, so as to divide it into two channels separate from each other and extending along substantially the entire discharge path. The partition has a "pinched" portion 6, into which the column is 40 driven by the convective forces, so that it is closely surrounded by matter. The partition, which is the refractory matter, is cooled by fluid (preferably air) circulated through the channel 7 above the partition.

In Figure 3 the envelope is a plain quartz tube 1, to the upper portion of which is applied along substantially the entire discharge path a closely 50 fitting metal member 8 furnished with a channel 9 through which water is circulated. This upper portion thus becomes the refractory solid matter. Alternatively the water cooling of the metal member may be replaced by air cooling by 55 means of fins forming part of it.

Having now particularly described and ascertained the nature of our said invention and in

what manner the same is to be performed, we declare that what we claim is:—

1. A high pressure vapor electric discharge lamp comprising a sealed envelope containing a gaseous atmosphere and having a pair of electrodes sealed therein, the line joining said electrodes having a transparent portion of said envelope on one side thereof and an artificially cooled portion of said envelope on another side thereof, and means to confine the discharge between said electrodes to an eccentric path within said envelope adjacent said artificially cooled portion thereof, whereby the discharge is stabilized and the transparent portion of said wall is maintained unobscured. 10 15

2. A high pressure vapor electric discharge lamp comprising a sealed envelope containing a gaseous atmosphere and having a pair of electrodes sealed therein, means to confine the discharge between said electrodes to an eccentric path within said envelope close to one wall thereof to stabilize said discharge and to reduce the heating of the opposite wall of said envelope, and means to force a flow of air over that portion of the envelope to which the discharge is adjacent in order to keep it below the softening temperature. 20 25

3. A high pressure vapor electric discharge lamp comprising a sealed envelope containing a gaseous atmosphere and having a pair of electrodes sealed therein, means to confine the discharge between said electrodes to an eccentric path within said envelope close to one wall thereof to stabilize said discharge and to reduce the heating of the opposite wall of said envelope, and 30 means to maintain that portion of the envelope to which the discharge is adjacent below the softening temperature, said means comprising a metal member in contact with that portion of said envelope and having means associated therewith to provide flow of a cooling fluid to remove heat from said metal members. 35 40

4. A high pressure vapor electric discharge lamp comprising a sealed envelope containing a gaseous atmosphere and having a pair of electrodes sealed therein, means to confine the discharge between said electrodes to an eccentric path within said envelope close to one wall thereof to stabilize said discharge and to reduce the heating of the opposite wall of said envelope, 45 and means to maintain that portion of the envelope to which the discharge is adjacent below the softening temperature, said means comprising a water cooled jacket in contact with that portion of said envelope. 50 55
